UNITED STATES PATENT OFFICE.

HENRY D. SCHALL AND RANSOM W. DAVENPORT, OF DETROIT, MICHIGAN, ASSIGNORS
TO DETROIT STOVE WORKS, OF DETROIT, MICHIGAN, A CORPORATION OF MICHIGAN.

GAS-RANGE.

1,299,623.

Specification of Letters Patent.

Patented Apr. 8, 1919.

Application filed January 31, 1916. Serial No. 75,417.

To all whom it may concern:

Be it known that we, HENRY D. SCHALL and RANSOM W. DAVENPORT, both citizens of the United States of America, residing at 5 Detroit, in the county of Wayne and State of Michigan, have invented certain new and useful Improvements in Gas-Ranges, of which the following is a specification, reference being had therein to the accompanying drawings.

The invention relates to gas stoves and has particular reference to the construction and arrangement of oven or broiler burners and the controlling valves therefor. It is the object of the invention to obtain better control of the oven or broiler burner; further to control this burner as well as all of the open-top burners of the range from the front thereof, all of the controlling valves being 15 arranged in alinement; and still further it is an object to facilitate the lighting of the burner and the easy detachment of the same for cleaning.

In the drawings:

25 Figure 1 is a perspective view of a gas range to which our improvements are applied;

Fig. 2 is a sectional plan view thereof;

Fig. 3 is a longitudinal section through 30 the lighter for the burner;

Fig. 4 is a cross section thereof.

In the present state of the art, with certain types of gas range it is customary to use a single burner for heating the bottom of 35 one oven and the top of the broiler or toaster oven. To distribute the heat uniformly over the bottom area it is usual to have a plurality of burner jet tubes in the form of a U-tube or otherwise connected to be controlled 40 from a single burner. This, however, has the disadvantage that it is difficult to obtain a low fire on account of the large open jet area; furthermore, as is usually the case, where the controlling valve is at the side of 45 the oven it is difficult to see the flame when manipulating the valve. With our improved construction this defect is overcome, first, by substituting two independently-controlled burners for the single-control U-tube burner, 50 and the easy manipulation is also facilitated by placing the controlling valves for both burners at the front rail of the stove or in alinement with the burners controlling the open top.

55 As shown, A is the frame of the stove, B

is the open top section, C is the baking oven arranged at one side of the open top and above the same, and D is the lower or broiler oven beneath the oven C and at the side of the pan or casing beneath the open top. The 60 ovens C and D are separated from each other by a sheet-metal partition E which is removable when desired to throw both compartments into one. At the front of the open top section is arranged the usual gas supply tube 65 F for feeding a series of burners G G', etc. controlled by valves H H', etc. The valves H^a and H^b for controlling the broiler and oven burner are also arranged in connection with the tube and in alinement with the 70 valves for the open top burners at the end adjacent to the oven. I and I' are gas tubes leading from the air-mixing chambers J into the compartment beneath the open top and then extending laterally at K and K' 75 through the side wall L of the oven and connecting therein with the burners M and M'. The opposite ends of these burners are supported upon a bracket N, while the tubes I and I' in passing into the oven are supported 80 on the slotted plate O clamped by a thumb-screw P to the side of the oven wall. This thumb-screw passes through a slot P' in the plate, which permits of a longitudinal adjustment thereof, the purpose of which is to 85 engage and disengage the ends of the tubes I and I' with the nozzles of their respective gas valves.

To facilitate the lighting of the burners M and M', we have arranged a pilot and 90 lighter tube Q which extends centrally from one burner to the other and extends forward in the oven to the front end thereof. This tube Q is preferably a cored casting having apertures R and R' therein for engaging upwardly-projecting nipples S on the burners M and M', thereby forming a gas connection. There is also a slit T formed by sawing which extends longitudinally of the tube Q so that by igniting the gas at the front of 95 the tube the flame will run along the slit to each of the burners M and M'. Also this tube operates to automatically light one 100 burner from the other.

With the construction as described, to attach and detach the oven and broiler burners they are first engaged with the slotted plate O, and the burners proper are inserted through the apertured side L of the oven into position, their ends being supported 110

upon the bracket N. The thumb-screw P secures the plate O in position and the slot P' therein permits of longitudinal adjustment of the tubes I and I' to engage the front ends thereof with the valve nozzles. Thus whenever it is necessary to clean the burners they may be quickly removed and replaced. The tube Q is also quickly assembled with the burners by merely engaging the apertures R and R' thereof with the nipples S and at any time when the burners are to be removed it may be lifted therefrom.

What we claim as our invention is:—

1. In a gas range, the combination with an open top section having a pan therebeneath and an oven section at the side of said open top section, of a burner for said oven extending into the latter through the side adjacent to said open top and at a point between the same and the pan therebeneath, a gas conduit extending along the front of said open top section, valves connected to said gas conduit having inwardly-extending gas discharge nozzles, a gas tube connecting said oven burner with the nozzle of the controlling valve therefor and engageable therewith by a longitudinal adjustment, and means engaging said tube at the point of entrance to said oven for securing the same, adjustable to permit of engagement and disengagement with said gas nozzle.
2. In a gas range, the combination with an open top section having a pan therebeneath and an oven section at one side thereof, of a gas conduit extending along the front of said open top section, valves connected with said conduit having inwardly-extending discharge nozzles, a plurality of burners for the open top section having tubes extending to the front and engageable with the nozzles of their respective valves, a gas burner projecting into said oven through the wall between the same and said open top and beneath the latter, said burner having a gas tube extending to the front and engageable with the nozzle of a controlling valve, an apertured plate secured to the side of said oven for supporting and securing said tube, and means permitting the adjustment of said plate to engage and disengage said tube from the gas nozzle.
3. In a gas range, the combination with an open top section and an oven section adjacent thereto, of a gas conduit extending along the front of said open top, valves con-

nected to said gas conduit, a plurality of said valves controlling the burners of the open top, oven burners comprising a plurality of independent sections, each projecting into the oven through the wall between the same and the open top section and having a forwardly-extending gas conduit for engaging a controlling valve, and a plate for securing said burners in position adjustable to permit of engagement and disengagement of the same with their controlling valves.

4. In a gas range, the combination with an oven, of a burner for said oven extending into the latter through a side wall of the oven and extending exteriorly of the oven to the front thereof, a controlling valve for said burner at the front of the oven, the burner being engageable therewith by a forward displacement, and means engaging said burner at its point of entrance to the oven for securing the burner at said point, said means being adjustable to permit of engagement and dis-engagement of the burner with the valve.

5. In a gas range, the combination with an open top section and an oven section adjacent thereto, having compartments respectively above and below said open top section, of a gas conduit extending along the front of the open top, a series of valves connected to said conduit, gas burners in the oven adjacent the juncture of said compartments and connections from said burners to certain of said valves.

6. In a gas range, the combination with an open top section, and an oven section adjacent thereto having compartments respectively above and below said open top section, of a gas conduit extending along the front of the open top, a series of valves connected to said conduit, gas burners in the oven adjacent the juncture of said compartments and connections from certain of said valves to said burners, said connections extending through a side wall of the oven, each burner and its connection being detachable as a unit.

In testimony whereof we affix our signatures in presence of two witnesses.
